UNITED STATES PATENT OFFICE.

HENRY GREEN, OF PEKIN, ILLINOIS, ASSIGNOR TO THE ACME HARVESTER COMPANY, OF SAME PLACE.

HAY-STACKER.

SPECIFICATION forming part of Letters Patent No. 683,600, dated October 1, 1901.

Application filed February 1, 1901. Serial No. 45,602. (No model.)

To all whom it may concern:

Be it known that I, HENRY GREEN, a citizen of the United States, residing at Pekin, in the county of Tazewell and State of Illinois, 5 have invented certain new and useful Improvements in Hay-Stackers; and I do hereby declare that the following is a full, clear, and exact description of the invention, which will enable others skilled in the art to which it applies to make and use the same.

This invention relates to improvements in hay rickers or stackers. One of its objects is to provide a construction that will require a minimum of power to operate it.

15 A further object is to simplify the construction of this class of machines without sacrificing rigidity or efficiency.

In the accompanying drawings, Figure 1 is a side view of my improved stacker in its normal position. Fig. 2 is also a side view of my improved stacker, showing its hay-carrier raised to the position for stacking. Fig. 3 is a plan view. Fig. 4 is a front view in part section. Fig. 5 is a perspective view of a 25 shifting support; and Fig. 6 is a perspective view of two separate portions of a supporting means, showing their relative positions.

In the several figures, A indicates the usual runners, which support two standards C C 30 near their forward ends by means of a cross-beam B. A horizontal rod D is carried in the said standards and supports at its ends an A-shaped frame E, which I shall term a "lever" in the accompanying claims, but refer to it in 35 this specification as a "frame." Between the upper ends of the said frame E are held two uprights G, whose lower ends are held by the said rod D, which passes therethrough. Between the upper extremities of said uprights 40 is carried a pulley F, as shown in Fig. 4. An arm H is pivotally attached to the said uprights G by suitable straps H', and the opposite end thereof is pivotally attached to the beam I, as shown in Fig. 1. The latter passes 45 backward between the uprights G, and carries a roller I' at its lower end, adapted to rest upon the track J, secured to the framework of the stacker, as clearly shown in Fig. 5. The extreme lower ends of the A-frame project below the rod D, upon which they are carried, and by means of arms K are connected

to the lower end of the said beam I, as shown in Figs. 1 and 2. A bail L is pivotally hung from the juncture of the bar H and beam I and pivotally attached at its lower ends to the 55 hay-carrier M. The latter is adjustable for length by the means ordinarily employed and the rear ends thereof are pivoted to supports N, erected on the frame, as shown. Suitable sheaves O are supported on a beam P, located 60 between the supports N, and a rope or cable Q passes over them and the pulley F of the A-frame E in such manner as to draw the said pulley F toward the sheaves O when the rope is pulled. The said carrier is provided with 65 the usual teeth, as shown, and suitably braced, so that it will not become racked or twisted. The uprights G, before described, are not absolutely necessary in the machine, but are employed as guides for the beam I, so that the 70 great weight which it is called upon to carry cannot bend or spring it out of shape, all of which will be readily understood.

The operation is as follows: In drawing on the rope the A-frame E is drawn toward the 75 sheave-wheels O, as before intimated and as shown in dotted lines in Fig. 1 and in full lines in Fig. 2. This pulls the arm H, and with it the beam I. This raises the carrier M by means of the bail L, the thrust being 80 put upon the said beam I. It will be observed that since the A-frame moves on the rod D its lower projecting extremities will be moved in the opposite direction or toward the front of the machine, and since these extremities 85 are connected directly with the beam I the lower end of the latter will also be moved and will, by means of its roller I', descend upon the track J described. The effect of this track movement is to apparently lessen 90 the length of the beam I with reference to the fixed length of the A-frame as said beam reaches the vertical position. The idea is to keep the upper ends of the said A-frame and the beam I in as direct line as possible, so 95 that by depressing the beam as described the above result will be as nearly realized as possible. It will be seen by referring to Fig. 1 that if the said beam remained in the position indicated on the track in full lines its 100 height would be considerably above that shown, and in consequence farther from the

direct pull of the A-frame; but by lowering said beam on its track better results are obtained. In full lines in said Fig. 1 the beam is of course made to overhang the load as far as possible, so as to lift it in a direct line. Then after being raised to about the dotted-line position shown it is apparently shortened in the manner and for the purposes described. In Fig. 2 the extreme position has been reached for dumping the hay upon the stack. In this position the carrier M is vertical or slightly beyond the vertical position, being carried there by the downward pull of the A-frame and arm H and bail L, as will be readily seen. The usual weight for returning the carrier to its normal position is indicated in the drawings, one end of its supporting-rope being attached to the carrier and the other to the frame of the stacker. It will be seen that the leverage between the pivotal support of the A-frame and the upper end of said frame is many times greater than between said pivotal support and the ends carrying the arms K. Consequently no loss of power is suffered, and this is especially evident when considering that the movement of the beam I is downward upon the track J when raising the load. When the load is delivered and the stacker is assuming its downward position or position of rest, the upward movement of the beam upon its track is of no consequence, as the weight of the hay-carrier in moving the A-frame upon its pivot will easily move said beam by means of the said arms K to its upward position upon the track. By this construction of the apparatus and the application of power thereto an advantage is attained without loss of efficiency at other positions. I may vary the construction somewhat and change the relative positions of the parts and may incline the track J at other angles than that shown without departing from the spirit of my invention.

I claim—

- 45 1. In a stacker, a support therefor, a lever pivotally mounted thereon, its lower ends depending below said pivot, an arm pivoted to the upper extremity, a beam pivoted to said arm, said beam adapted for changing its position by a shifting movement at the lower extremity for the purposes set forth, connection between said shifting end of said beam and the depending extremities of the said lever, a hay-carrier pivoted to the stacker-support and having connection with the upper extremities of the said arm, and mechanism for operating said stacker substantially as set forth.
- 50 2. In a stacker, a support therefor, a lever pivotally mounted thereon, extensions on said lever below said pivotal points, a beam adapted for a changing movement at its lower end behind the pivotal support of the lever, an arm for connecting the upper end of the lever and the upper end of said beam, a connection between the lower end of the beam and the extensions of the said lever, a hay-

carrier pivoted on the machine, a connection between said upper end of the beam and the carrier and mechanism for operating the stacker substantially as set forth.

3. In a hay-stacker, a support therefor, a lever pivotally mounted thereon, consisting of the angling portions thereof, the vertical portions between the latter, an arm pivoted to the upper end of the lever, a beam pivoted to the free end of the arm and extending rearwardly between the said vertical portions of the lever, a roller on the lower end of the beam, a track for the roller, a hay-carrier pivoted to the stacker-support, connection between said carrier and the juncture of the said beam and arm, and mechanism for operating the stacker substantially as and for the purposes described.

4. In a hay-stacker, a support therefor, a lever pivotally mounted thereon and having extensions below the said pivots, a beam occupying a position at an angle to the said lever, the lower end thereof being behind the said lever, the upper end being forward of said lever, an arm connecting the upper end of the lever and the forward end of the beam, a roller on the lower end of the beam, a track for said roller, connection between the lower end of the beam and the projecting ends of the lever, a hay-carrier, means for changing its length a connection between the carrier and the upper forward end of the beam, and mechanism for operating the stacker.

5. In a stacker, the combination of the supports, the lever pivotally mounted thereon and having projecting ends below the pivots, a beam located at an angle to the lever, its lower end projecting rearwardly beyond the said lever, a roller on said lower end, a track for supporting said roller, connection between the said lower end of the beam and the projecting ends of the lever, an arm for connecting the upper end of the lever and the upper end of the beam, a hay-carrier pivoted upon the support, a bail connecting the beam and arm with said carrier and mechanism for operating the stacker as set forth.

6. In a stacker, the combination of supports therefor, a lever E pivotally mounted thereon and having projecting ends below the pivotal points, a beam I located at an angle to the lever, and extending beyond it in a rearward direction, a roller I' on the lower end thereof, a track J for the same, an arm H connecting the upper end of the lever with the upper end of the said beam I, a hay-carrier M pivoted to the stacker-frame, and a bail for connecting the arm H with the said carrier M all arranged substantially as and for the purposes set forth and described.

In testimony whereof I affix my signature in presence of two witnesses.

HENRY GREEN.
